UNITED STATES PATENT OFFICE.

SULO ATTILA, OF FRANKFORT-ON-THE-MAIN, GERMANY, ASSIGNOR TO THE FIRM OF DEUTSCHE-ELEKTRO-SPARLICHT-GESELLSCHAFT, OF FRANKFORT-ON-THE-MAIN, GERMANY,

TRANSFORMER AND METHOD OF MAKING THE SAME.

1,260,743.

Specification of Letters Patent. Patented Mar. 26, 1918.

Application filed July 29, 1909. Serial No. 510,194.

To all whom it may concern:

Be it known that I, SULO ATTILA, a subject of the grand duke of Finland, and a resident of Frankfort-on-the-Main, Germany, have 5 invented certain new and useful Improvements in Transformers and Methods of Making the Same, of which the following is a specification.

This invention relates to transformers and 10 like apparatus, and particularly to transformers of small capacity which are adapted for use with metallic filament lamps.

It is well known that low voltage metallic filament lamps are not only more efficient 15 than high voltage lamps, but since the filament is shorter it can be more easily supported and can also be made of smaller candle power. Low voltage however has the objection that the line losses are excessive. 20 If however a transformer is mounted directly at each lamp, then such objection is avoided since the line voltage can then be relatively large while this line voltage can be reduced at the lamp.

25 Where such small transformers are used it is exceedingly difficult to wind them if the core is in one piece since the holes are small. This difficulty is great even where they are wound by hand.

30 One of the objects of this invention therefore is to construct a transformer or like apparatus which can be easily wound and in which the magnetic joints are well made, and another object is to provide a method 35 of manufacturing such an apparatus.

The invention will be described in connection with the accompanying drawings, in which:

Figure 1 is a section on the line A—A, 40 Fig. 2, and shows one form of transformer which is of the inclosed coil type;

Fig. 2 is a section on the line B—B, Fig. 1;

Figs. 3 to 6, inclusive, are views similar to Fig. 1, showing different forms of inclosed 45 coil transformers;

Fig. 7 is a view similar to Fig. 1, showing an open or exposed type of transformer;

Fig. 8 is a view similar to Fig. 1 showing a three-phase transformer;

50 Fig. 9 is a view similar to Fig. 1 showing another form of inclosed coil transformer;

Figs. 10 and 11 illustrate a method and apparatus for assembling the core plates of the type of transformer illustrated in Figs.

3 to 6 inclusive and Figs. 8 and 9; Fig. 10 55 being a section on the line C—C, Fig. 11, and Fig. 11 being a section on the line c—c Fig. 10;

Fig. 12 illustrates a method and apparatus for assembling the yoke plates; 60

Fig. 13 shows the core with a winding thereon;

Figs. 14 and 15 illustrate one method of winding the core;

Fig. 16 shows the type of transformer of 65 Fig. 7 with the core and yoke partly wound;

Figs. 17 and 18 illustrate a method and apparatus for assembling the yoke plates of the form shown in Figs. 7 and 16, Fig. 17 70 being a section on the line D—D, Fig. 18, Fig. 18 being a section on the line E—E, Fig. 17;

Fig. 19 illustrates a method of winding the assembled yoke;

Figs. 20, 21 and 22 illustrate a method 75 and apparatus for assembling the core plates of the form shown in Figs. 7 and 16, Fig. 20 being a section on the line F—F, Fig. 21, Fig. 21 being a section on the line G—G, Fig. 20, and Fig. 22 being a section on the 80 line H—H, Fig. 20;

Fig. 23 illustrates the method of winding the assembled core;

Figs. 24 and 25 illustrate the method of bringing together and assembling the as- 85 sembled core and yoke; and

Figs. 26 to 28 inclusive show different forms of transformers which form the subject-matter of this invention and which may be made according to the method to be de- 90 scribed.

Referring to the drawings, and more particularly to Figs. 1 and 2, it will be seen that the transformer there shown is of the inclosed coil type. The core of the transformer is made up, as usual, of plates or laminæ and comprises a core proper designated by the reference character 1, and a yoke 2, which surrounds the core and the coil 3 wound thereon.

100 It will be readily seen that where this transformer is small, and if both the core and the yoke are made in a single piece, that is from single stampings, it is exceedingly difficult to place the winding on the core in view of the small space allowed. The drawings illustrate a form which shows in full size a transformer having a capacity of 40

watts and is therefore of proper size for metallic filament lamps.

In accordance with this invention the plates or laminae are stamped so that the core and yoke can be assembled separately whereby the winding of the coil on the core is greatly facilitated, as will appear later.

Figs. 10 to 15 inclusive illustrate a method of manufacturing the transformer shown in

- 10 Figs. 1 and 2. The core plates or laminae are stamped in the usual way and then assembled in a sleeve 4. The interior of the sleeve corresponds to the outside contour of the core plates so that these core plates will
- 15 be assembled and alined therein as will be seen from Figs. 10 and 11. After these core plates are thus alined in the sleeve they are tightly clamped together by means of a pressure head 5 which screws into the sleeve.
- 20 The sleeve is provided with recesses 6 for the reception of clamps 7. After the plates have been assembled in the sleeve and compressed the clamps are slipped over the ends of the assembled core plates as shown in
- 25 Figs. 10 and 11, and the assembled core may then be removed from its assembling device, the clamps holding the plates rigidly together. These clamps are preferably provided with centers so that the assembled core
- 30 may be placed in a lathe or in a winding machine as shown in Figs. 14 and 15, so that the coil 3 can be wound thereon after suitable insulation has been applied to the core.

The yoke plates are assembled on a mandrel 9, which is guided in a sleeve 8. In this case however the interior surfaces of the yoke plates are alined by the mandrel, the internal diameter of the sleeve being larger than the outside diameter of the yoke

40 plates. After the yoke plates have thus been assembled in alined relation on the mandrel and in the sleeve, they are compressed by means of a pressure head 10, as shown in Fig. 12.

- 45 The clamps 7 are now removed from the assembled and wound core since the winding and insulation thereon will be sufficient to hold the core plates together. The assembled core is now placed in position in
- 50 the head 10 and above the assembled yoke while it is still on the mandrel and in the sleeve 8, and the parts are forced together by a suitable press, the mandrel 9 receding as the core is forced in place, and the core
- 55 being guided by the interior wall of head 10. It will be understood that the external diameter of the core is slightly greater than the internal diameter of the yoke so that the parts will be forced together, making a
- 60 pressed or forced fit. The coöoperating and engaging surfaces of the yoke and core may of course be machined in order to make a more accurate fit. After the parts have thus been forced together the whole may be
- 65 removed from the sleeve 8.

The yoke and core thus assembled will be firmly held together by the pressed joint. The core plates of course are held together by the winding and the yoke plates will be held together by the core plates so that no bolts or other fastening means will be necessary. The joint between the parts will be exceedingly efficient and will have a low magnetic reluctance.

Instead of forcing the parts together by pressure the assembled yoke may be shrunk on the core. This may be accomplished by heating the yoke as assembled in its sleeve (Fig. 12) until it expands sufficient to permit the assembled core to be placed therein. After the parts have been thus assembled the subsequent cooling will shrink the yoke tightly on the core. The temperature to which the yoke must be raised need of course not be very high since a slight expansion and contraction is sufficient to make a good joint.

Figs. 3 to 6, inclusive, and 8 and 9 show different forms of this invention but their construction will be obvious from the illustration. It will be seen that the same method of assembling may be applied to these forms as to the construction shown in Fig. 1.

It is advantageous in the manufacture of apparatus of this type to stamp the core and plates out of the same material that the yoke is stamped out of. In accordance with this invention therefore the core plates may be stamped from the same material as the yoke plates and the parts can therefore be assembled and subsequently forced together. This results in a great saving of material.

Figs. 7 and 16 show a transformer of the open or exposed coil type. In this case the yoke 11 and the core 12 are divided as shown so as to be of open construction, thereby permitting the parts to be wound in a lathe or other winding machine.

The core is assembled in a similar sleeve 4, as shown in Figs. 20 to 22, and after the plates have been compressed the clamps 7 are slipped on, these clamps being provided with centers whereby the assembled core may be placed in a lathe or other winding machine and the coil 3 wound in place, after suitable insulation has been applied to the core. In this case also the sleeve 4 is constructed to engage the joint-forming surfaces of the core so as to properly aline the core plates.

The yoke is assembled in a similar manner as shown in the preceding construction and the form of mandrel 9 and sleeve 8 is shown in Figs. 17 and 18. The yoke plates are alined in the sleeve and on the mandrel as in the preceding method, clamped by the pressure head 10 and the clamps 7 applied. The plates in this case also are assembled with their joint-forming surfaces in engage-

ment with the mandrel 9 so as to be properly placed in assembled and alined relation, and the wound core can be forced in the assembled yoke in its sleeve, or the yoke can be shrunk on the core as in the preceding method. It will be noted that the mandrel in this case is provided with a recess for the coil and that the clamps 7 can remain on the core while it is being forced in place 10 in the yoke.

In the construction shown in Figs. 26 and 27 the yoke plates are made of two parts 2', 2''. The separate halves of the yoke are assembled and can then be wound with wire. 15 In this way a permanent pressure is produced between the core and yoke so as to form a good joint having a minimum magnetic reluctance. In Fig. 26 the yoke embraces the ends of the core, while in Fig. 27 20 the ends of the yoke sections abut against the lateral core faces.

If inclosed coil transformers of the kind described and illustrated in Figs. 1 to 6, 8 and 9 are to be suspended direct it is advisable to arrange the holes for bolts which 25 pass through the casing or yoke plates at the point where the magnetic flux is a minimum, that is on the axis of the core. This is shown in Fig. 28 where the bolt holes are 30 located on the diameter 14, 14.

In manufacturing small inclosed coil transformers of the above mentioned kind it is preferable to provide the yoke plates 2 at the point at which the winding 3 of the 35 core plates 1 join with recesses 13, as shown in Figs. 1, 3, 4, 5, 8 and 9. By means of this construction an effective stamping is obtained and the core plates can be readily forced into the yoke plates. This is also 40 advantageous if the joint faces are to be machined since only the actual engaging parts or faces of the yoke will be the only machined parts. It will be seen that the yoke is provided with portions 15, 15 which 45 are free from the coil so that the bearing faces are provided for a press head when the parts are to be forced together.

It will thus be seen that this invention obtains the results aimed at. A transformer 50 is produced in which the joints are well made so as to have a minimum magnetic reluctance, and the parts are so constructed that the winding can be applied thereto and the parts assembled with the minimum of 55 expense no matter how small the apparatus is.

In both press and shrinkage fits the outer member of the joint hugs the inner member. In a press fit the outer member is bored 60 to a smaller diameter than the inner member and is slightly expanded by forcing the inner member into it, while in a shrinkage fit the outer member is expanded by heat and subsequently contracts when the 65 parts are cooled. The opening in the lami-

nated yoke is slightly smaller than the largest dimensions of the core and when the two laminated parts are united they are held together as a permanent unitary laminated structure solely by the mutual frictional edge engagement of the laminations of the yoke and core respectively. When the laminated yoke and laminated core are united the fibers adjacent the abutting edges will be under permanent compression in the core 70 and under permanent tensile stress in the yoke.

Having thus described the invention, what is claimed is:

1. The herein described method of making 80 transformers which comprises forming a series of core laminæ, compressing the same together and winding a coil thereon intermediate of the ends while maintaining the laminæ under compression, forming a series of yoke laminæ and assembling the same under compression, pressing the assembled core laminæ and the winding thereon into place in an opening formed in the assembled yoke laminæ and transversely of the latter, 90 whereby a permanent unitary laminated structure having a winding thereon is obtained and whereby the sole means for holding the laminated core and laminated yoke together comprises the mutual frictional edge engagement of said core laminæ 95 and yoke laminæ.

2. A transformer comprising a core consisting of a series of superposed laminæ compressed together, a yoke consisting of a 100 series of superposed laminæ compressed together and forming when assembled a laminated yoke having an opening therein extending transversely of the plane of the laminæ and adapted to receive the laminated core, the dimensions of said opening in the yoke being slightly smaller than the dimensions of said core whereby considerable pressure is required to force said core into said opening and whereby the yoke and core 105 are held together solely by mutual frictional edge engagement of the laminæ comprising the core with the laminæ comprising the yoke and the metal at the joint therebetween being placed under permanent stress. 115

3. A small transformer for use with low voltage metallic filament lamps and equivalent translating devices and adapted to be mounted directly on a lamp setting, said transformer comprising a series of superposed core laminæ compressed together, a series of superposed yoke laminæ compressed together and forming when assembled a laminated yoke having an opening therethrough slightly smaller than the largest 125 dimension of the core and adapted to receive the laminated core, the core and yoke being held together solely by mutual frictional edge engagement of the laminæ comprising the core with the laminæ comprising the 130

yoke whereby a permanent unitary laminated structure is formed, and a winding on the core.

4. The method of making a laminated structure having a laminated core and a laminated yoke which comprises forming a series of core laminæ and compressing them together to provide a laminated core, forming a series of yoke laminæ and compressing them together to provide a laminated yoke, winding a coil on one of said series of compressed laminæ while maintaining the laminæ under compression, forcing the laminated core into the laminated yoke, while the laminæ thereof are held under compression, by causing a relative movement of the core and yoke transversely of the planes of the laminæ thereof.
5. A transformer comprising a plurality of parts and including a series of super-

posed core laminæ compressed together and forming a laminated core, a series of superposed yoke laminæ compressed together and forming when assembled a laminated yoke constructed so that the core contacting surfaces thereof shall embrace the laminated core, the core and yoke being held together solely by mutual frictional edge engagement of the laminæ comprising the core with the laminæ comprising the yoke, whereby a permanent unitary laminated structure is formed, and a winding on one of said parts.

In testimony whereof I have signed my name to this specification in the presence of two subscribing witnesses.

SULO ATTILA.
